Primary Examiner—Doris Clark(74) *Attorney, Agent, or Firm*—Gardere Wynne Sewell LLP(57) **CLAIM**

The ornamental design for a building element, as shown and described.

DESCRIPTION

FIG. 1 is a front perspective view of a building element; FIG. 2 is a plan view of the building element shown in FIG. 1; FIG. 3 is a first end view of the building element shown in FIG. 1; FIG. 4 is a second end view of the building element shown in FIG. 1; FIG. 5 is a first side view of the building element shown in FIG. 1; FIG. 6 is a second side view of the building element shown in FIG. 1; FIG. 7 is a bottom view of the building element shown in FIG. 1; and, FIG. 8 is a back perspective view of the building element shown in FIG. 1.

For FIGS. 1-8, lines shown as broken are for illustrative purposes only, showing the environment, and form no part of the claimed design.
